DISPENSER FOR PRESSURE SENSITIVE TAPE

Gilbert W. Lindemann and Raymond B. Kruskopf,
St. Paul, Minn.

Application September 14, 1956, Serial No. 42,930

Term of patent 14 years

(Cl. D74—1)

Fig. 1 is a perspective view showing one side of a dispenser for pressure sensitive tape embodying our new design; and

Fig. 2 is a perspective view of the other side thereof.
We claim:

The ornamental design for a dispenser for pressure sensitive tape, substantially as shown.
